UNITED STATES PATENT OFFICE

ARTHUR HEILAND, OF BERLIN-RANGSDORF, GERMANY

AUTOMATIC VENDING MACHINE

Application filed October 11, 1928, Serial No. 311,894, and in Germany April 22, 1928.

The invention relates to automatic vending machines, capable of dealing with substantially flat goods, for example folded journals, magazines and the like, which are delivered from a pile within the machine.

The invention is concerned with machines of the kind in which the separate removal of the articles from the pile is effected by means of a flexible member, which I shall refer to generally as a string, having one end attached to a support on which the pile rests, and the other end attached to a rotatable drum on which the string can be wound, in the form of a regular helix, the string passing in zig-zag through the pile so that it forms an open loop round each article except the one on top, with the result that an upward pull exerted on the string by rotation of the drum causes the article on top to be lifted and thrown off the pile.

The object of my invention is to improve the reliability and general utility of machines of this kind.

An embodiment of apparatus according to the invention is shown in the accompanying drawing.

Fig. 1 is a front view of some of the principal parts of the mechanism, and

Fig. 2 is a side view thereof.

Fig. 3 shows the drum, partly broken away, with certain associated parts, and

Fig. 4 is a side view thereof.

Figs. 5 and 6 show the drum to a larger scale, and

Figs. 7 and 8 illustrate a device for traversing the drum.

Figs. 9 and 10 illustrate a modification enabling the circumferential part of the drum to be changed, and

Fig. 11 illustrates a modification enabling the effective circumference of the drum to be regulated.

Fig. 12 shows a device for attaching the string to the drum.

Figs. 13 and 14 are two views of part of the mechanism whereby inserted coins cause delivery of goods.

Fig. 15 shows the pile of goods on its support, with the string, and

Fig. 16 is a perspective view of the outside of part of the machine.

The apparatus has a casing, in which is a table Z for the journals shown in Fig. 15. These are piled one upon the other, and a string k having one end attached to the table Z passes in zig-zag through the pile, from bottom to top, so that it forms an open loop around each journal except the one at the top. The string passes over a guide roller c, and its upper end is attached to a drum b having a helical groove, in which the string can be wound by rotating the drum. As shown in Figs. 1 to 6 the drum is slideable on a shaft w having a longitudinal groove y into which engages the tip of the screw x screwed into a tubular boss at one end of the drum. This screw causes the drum to rotate with the shaft, but does not prevent axial movement of the drum on the shaft and axial movement of the drum is caused by a fork g engaging the helical groove.

In the modification shown in Figs. 7 and 8 the drum, designated b¹ in Fig. 7, has at one end a tubular boss v with an external screw thread, the pitch of the screw thread being equal to that of the helical groove on the drum. Engaged with this boss is a nut u held by two pivoted arms s, so that it cannot rotate, and consequently causes axial displacement of the drum when the drum is rotated.

The journals are lifted off the pile by the pull of the string when the drum is rotated for winding the string on it, and the journals being of uniform size, and uniformly folded, the same length of string must be wound on the drum for lifting each journal. In order that the same amount of rotation will lift a journal of another size, if the machine is to deal with journals of such other size, the diameter of the drum must be changed. This may be done by changing the drum, or may be effected by providing a helically grooved, two-part shell m¹, m², as shown in Figs. 9 and 10, this shell being placed on the drum, or removed, as required. It may be fixed to the drum by screws or other convenient means. Fig. 11 shows a modification, in

which the drum has a core b^2 with a disk p fixed to each end thereof. Each of the disks has two arms p^1, p^2 , to which two shell members m^{21} and m^{11} are connected by pivots q^1 and q^2 respectively. These shell members form the circumferential part of the drum, and can be rocked on their pivots by means of a turn-buckle r , to increase or reduce the effective circumference of the drum. A scale 10 may be marked in some convenient position to indicate the effective circumference.

To enable the string to be made taut, in case it has become stretched, the drum may be connected to the shaft w by means of a 15 coupling enabling it to be unfastened and rotated independently of the shaft, the drum being re-fixed to the shaft when the string is taut.

When a fresh supply of journals is to be 20 placed in the machine the string k is pulled, so that it is unwound from the drum. The drum, by means of a train of gears l , then rotates a shaft n (Fig. 2), on which is wound a cord o having a weight i attached thereto. 25 The weight is by this means lifted. Rotation of the drum in the opposite direction is prevented by a spring loaded catch h engaging a notched wheel f , which is fixed to a pinion in mesh with one of the gear wheels l .

30 To save time in inserting fresh journals into the machine, a fresh string k may be used for each pile of journals, and may be looped round the journals outside the machine, the ends being attached to the table Z and drum b respectively after insertion into the machine. Fig. 12 shows for this purpose a lug t on the tubular boss of the drum, with a part t^1 projecting over the drum to guide the string, and an eye t^2 for attaching the 35 hook.

The casing has a plurality of coin slots for the insertion of coins of different denominations, appropriate coin-testers being provided, and plates with directions for payment being affixed to the outside of the casing. The 40 coins inserted into each slot pass through a chute to a balance arm, and a coin or coins of the prescribed weight actuate this balance so that the drum is released for delivery of 45 a journal. The balance device can be regulated to respond to coins of different weights, or different numbers of coins, according to the price of the journal to be sold.

As shown in Figs. 1, 13 and 14 a chute receiving the coins has projecting into it a pin d for arresting the coins. This pin is vertically adjustable, according to the number of coins required for payment of a journal, and it is so adjusted that all the coins but 50 one remain temporarily resting on it, and fill that part of the chute which is above the pin, so that the last coin is deflected into another chute, through which it drops to the till. This last coin, on its way to the till, deflects 55 the arm projecting from the catch h , so that

the catch is temporarily disengaged from the wheel f . The drum is then rotated by the weight i till the catch h re-engages the wheel f , and by this means a journal is delivered. The rotation of the shafts w causes a cam e 70 (Figs. 1, 13 and 14) to rock a lever and temporarily withdraw the pin d from under the coins which it supports, so that these coins also drop into the till.

The journals lifted off the pile by the pull 75 of the string k fall on to an inclined guide way a (Fig. 15), which guides them to the delivery aperture of the machine. It will be noted that owing to the zig-zag course of the string through the pile the journals fall 80 off alternately at the back and front of the pile. At the back of the pile there are several pivoted rods 30 suspended from brackets, so that the journals falling off at the backs strike these rods, and not the back of 85 the casing. The guide way a is convex, and in order to provide an adequately steep guide for the journals falling off in front of the pile the guide way has a downward bend at the front part thereof.

It will be understood that the casing may have several compartments, for different journals, each with the appropriate devices for payment and delivery.

A specimen of each journal on sale may be 90 exposed to view behind a window in front of the casing, as shown in Fig. 16, and at the sides there may be windows behind which notices, advertisements, telegrams or the like are placed on view. Such notices and the 95 like may be attached to an endless band 11 on rollers 12 and 13, one of the rollers having a crank outside the casing, so that the band can be made to travel past the window, exposing the notices to view in succession.

What I claim as my invention and desire to secure by Letters Patent of the United States is:—

1. In an automatic vending machine the 110 combination of a support for a pile of goods, a rotatable drum, a lock restraining said drum from rotation, a device for releasing said lock, means whereby the drum is moved axially during rotation thereof, and means for attaching to said support and drum respectively the ends of a string placed in open loops round goods on the support, so that pulls exerted on the string by rotation of the drum throw the goods in succession off the 115 pile.

2. The combination claimed in claim 1, the drum having a helical groove for the winding of string thereon.

3. In an automatic vending machine the 125 combination of a support for a pile of goods, a rotatable drum, gravity actuated means for rotating said drum, a lock restraining said drum from rotation, a device for releasing said lock, means whereby the drum is moved 130

axially during rotation thereof, and means for attaching to said support and drum respectively the ends of a string placed in open loops round goods on the support, so that pulls exerted on the string by rotation of the drum throw the goods in succession off the pile.

4. In an automatic vending machine the combination of a support for a pile of goods, a rotatable drum of variable circumference, a lock restraining said lock from rotation, a device for releasing said lock, means whereby said drum is moved axially during rotation thereof, and means for attaching to said support and drum respectively the ends of a string placed in open loops round goods on the support, so that pulls exerted on the string by rotation of the drum throw the goods in succession off the pile.

20 5. In an automatic vending machine the combination of a support for a pile of goods, a rotatable drum having a detachable shell, a lock restraining said drum from rotation, a device for releasing said lock, means whereby said drum is moved axially in the course of rotation thereof and means for attaching to said support and drum respectively the ends of a string placed in open loops round goods on the support, so that pulls exerted on the string by rotation of the drum throw the goods in succession off the pile.

6. In an automatic vending machine the combination of a support for a pile of goods, a rotatable drum, a lock restraining said drum from rotation, means for releasing said lock, means whereby said drum is moved axially during rotation thereof, and means for attaching to said support and drum respectively hooks at the ends of a string placed in open loops round goods on the support, so that pulls exerted on the string by rotation of the drum throw the goods in succession off the pile.

45 In witness whereof I have signed this specification.

ARTHUR HEILAND.
